United States Patent Office

Des. 213,070
Patented Dec. 31, 1968

213,070

DISPENSING MACHINE

Curtis Lane, Riverdale, N.Y., and Kenneth Glenby, Wood-cliff Lake, N.J., assignors to Lanex Importing Company, Lodi, N.J.

Filed Dec. 26, 1967, Ser. No. 9,928

Term of patent 14 years

(Cl. D52—3)

The figure is a front perspective view of a dispensing machine showing our new design.

The side of the dispenser not shown is substantially the same in appearance as the side shown.

The back and top of the dispenser are substantially rectangular and are plain and ornamented.

We claim:

The ornamental design for a dispensing machine, as shown and described.
